UNITED STATES PATENT OFFICE.

GEORG KARL WILHELM JOHANSON, OF LIDINGO, SWEDEN, ASSIGNOR TO AKTIEBOLAGET
GASMÄTARE, OF STOCKHOLM, SWEDEN, A CORPORATION OF SWEDEN.

GAS METER.

Original No. 1,417,998, dated May 30, 1922, Serial No. 321,100, filed September 2, 1919. Application for
reissue filed March 26, 1926. Serial No. 97,798.

The invention relates to a diaphragm-gas meter provided with two measuring chambers and with valves which by the diaphragm through the action of a spring are 5 instantaneously reversed, the said spring being provided between the swinging ends of two turning levers, the one of which is connected with the diaphragm and the other with the valves. Gas meters of this type 10 hitherto known have the disadvantage, that the resistance of the spring against the movements of the diaphragm changes within a wide margin, with the result, that the gas pressure in the pipes connected to the meter 15 and consequently also upon the lights becomes uneven.

The object of this invention is to remove the said disadvantage, the principal feature of the invention being that two levers one 20 actuated by the diaphragm and the other actuating the valves cross one another and are connected by a spring. It is thereby attained, that the effect of the spring does not change appreciably during the movement of the diaphragm but in the contrary its tension remains as even as possible, so that practically also the resistance against the movements of the diaphragm and consequently the gas pressure upon the lights 25 will remain uniform.

In the accompanying drawing an embodiment of the invention is shown by way of example. Fig. 1 shows a cross section of a gas meter according to the invention, and 30 Fig. 2 shows a plan view of the meter with the upper portion of the casing and the diaphragm removed. Figs. 3 and 4 are details; Fig. 3 showing a section of the valve, and Fig. 4 showing a plan view of the elastic 35 spring in the same.

The gas meter shown is provided with two measuring chambers 1 and 2 which are located in a common casing 3. The two measuring chambers are separated by a partition which consists of a flexible diaphragm 4 of gas-tight material. The gas inlet 5 opens into a chamber 6 beneath the bottom of the casing, the communication of said chamber with the two measuring chambers 1 and 2 45 being controlled by two inlet valves 7 and 8, respectively, whereas the gas outlet 9 leads from another similar chamber 10, the communication of which with the measuring

chambers 1 and 2 is controlled by two outlet valves 11 and 12, respectively. All said 55 valves are made as disk valves, and each separate valve consists of a piece of leather or the like 13 which is stretched over a resilient or elastic wire ring 14, as shown in Figs. 3 and 4, so that the valve becomes light 60 and works silently. The two inlet valves 7 and 8 are secured respectively to the ends of a two-armed lever 16 which turns on a pivot 15 in such manner that when the valve 7 is closed, the valve 8 is open, and vice versa. 65 The valves 11 and 12 are supported in similar manner on a lever 18 turning on the pivot 17 so that they will be opened and closed alternately. The inlet valves 7 and 8 close against their seats from above, whereas the 70 outlet valves 11 and 12 close from below, as shown in Fig. 1.

The two inner valves 8 and 12 which control the connection with the measuring chamber 2, are coupled together by means of 75 a rod 19 which is preferably slightly elastic and the middle point of which is connected with one end of a two-armed lever 21 turning on the pivot 20. To the opposite end of 80 said lever one end of a helical spring 22 is secured the other end of which is secured to the free end bent downwards of a one armed lever 23 turning on the pivot 24. The said helical spring pulls on the free ends 85 of the two levers 21 and 23 in the direction towards their axes of turning 20 and 24, respectively. Consequently, the levers 21 and 90 23, are so related that lines connecting their fulcrum and the fixing points respectively of the spring cross one another in the limit 90 positions of the levers. The lever 23 is connected with the diaphragm 4 by means of a link 25, and supports a guide plate 26 which cooperates with two hooks 27 turning on the pivot 20 and rigidly connected with the lever 95 21 in such manner that said plate prevents the lever 21 from turning until the lever 23 has turned so far upwards or downwards that the hooks 27 may pass the upper or the lower edge of the plate.

The device above described operates in the following manner:

When the various parts occupy the positions illustrated in the drawing the valve 7 is closed, the valve 8 is open, the valve 11 is 105 open, and the valve 12 is closed. The gas

inlet 5 thus communicates with the measuring chamber 2 beneath the diaphragm 4, whilst the measuring chamber 1 communicates with the outlet 9. The gas then flows into the chamber 2 and forces the diaphragm 4 upwards, so that the gas in the chamber 1 is driven out through the outlet 9. When the diaphragm moves upwards it brings along the lever 23, which will thus turn upwards on its pivot 24. The spring 22 is thereby stretched. The lever 21 will remain in the position shown, however, as the guide plate 26 prevents the hooks 27 from turning to the left in Fig. 1, until the lever 23 has moved so far upwards that the hooks 27 may move past the lower edge of said plate. The free end of the lever 23, that is to say, its point of attachment to the spring 22, has then also moved so far upwards that it is located above the turning pivot 20 of the lever 21, consequently, when the plate 26 releases the hooks 27 the lever 21 will rapidly turn in a counter-clockwise direction in Fig. 1 through an angle which is dependent upon the stroke of the valves and the elasticity of the rod 19. The levers 16 and 18 are simultaneously turned in such manner that the valves 8 and 11 previously open become closed, whereas the valves 7 and 12 previously closed are opened. The measuring chamber 2 which is filled with gas, is thus brought into communication through the valve 12 with the outlet 9, while the empty measuring chamber 1 is connected through the valve 7 to the inlet 5. The gas now flows into the chamber 1 and forces the diaphragm 4 downwards bringing along the lever 23 until the hooks 27 can move past the upper edge of the plate 26, when the lever 21 and thus also all valves are again thrown back to the positions shown in Fig. 1. In this manner the measuring chambers 1 and 2 are alternately filled and emptied. On account of the spring 22 inserted between the diaphragm and the valve, the movements of the valves take place very rapidly and at definite moments of time which are accurately determined by the movements of the plate 26 and thus also of the diaphragm. If a suitable counter is attached to the lever

21 the measuring results indicated on such counter will be very reliable.

I claim:

1. In a gas meter, the combination of two measuring chambers, a movable diaphragm 55 separating said chambers, an inlet to said chambers, an outlet from said chambers, valves between each of said chambers and said inlet and said outlet, a spring mechanism between said diaphragm and said 60 valves comprising a lever and means whereby by said lever is connected with the diaphragm, a second lever, means whereby said last named lever is connected with the valves, a spring connecting the said second 65 lever to a point on the first named lever remote from its fulcrum, said levers being so related that lines connecting their fulcra and the fixing points respectively of the spring cross one another in the limit positions of the levers, and means for locking 70 said second lever against movement during the movement of the diaphragm until it reaches its limit positions of movement.

2. In a gas meter, the combination of two 75 measuring chambers, a movable diaphragm separating said chambers, an inlet to said chamber, an outlet from said chambers, valves between each of said chambers and said inlet and said outlet, a spring mechanism 80 between said diaphragm and said valves comprising a lever and means whereby by said lever is connected with the diaphragm, a guide member on said lever, a second lever, means whereby said last named 85 lever is connected with the valves, a spring connecting the said second lever to a point on the first named lever remote from its fulcrum, said levers being so related that lines connecting their fulcra and the fixing 90 points respectively of the spring cross one another in the limit positions of the levers, and locking hooks connected with said second lever and cooperating with said guide member in such manner as to prevent said 95 second lever from turning until the lever first mentioned occupies its limit positions.

In testimony whereof I have hereunto affixed my signature.

GEORG KÄRL VILHELM JOHANSON.
